CLAIM

The ornamental design for light panel, as shown and described.

DESCRIPTION

FIG. 1 is an isometric view of light panel showing my new design;

FIG. 2 is a front elevational view thereof;

FIG. 3 is a rear elevational view thereof;

FIG. 4 is a right elevational view thereof;

FIG. 5 is a left side elevational view thereof;

FIG. 6 is a top plan view thereof;

FIG. 7 is a bottom plan view thereof; and,

FIG. 8 is an isometric view thereof, shown in an environment of use.

The broken lines in FIG. 8 depict environmental subject matter only that forms no part of the claimed design.
